L. LEBAU.
GAS HEATER.
APPLICATION FILED AUG. 19, 1919.

1,342,121.

Patented June 1, 1920

Louis Lebau,
334 - *Asst. to Mr. Justice*
Attorney

UNITED STATES PATENT OFFICE.

LOUIS LEBAU, OF PITTSBURGH, PENNSYLVANIA.

GAS-HEATER.

1,342,121.

Specification of Letters Patent. Patented June 1, 1920.

Application filed August 19, 1919. Serial No. 318,600.

To all whom it may concern:

Be it known that I, LOUIS LEBAU, a citizen of the United States, residing at Pittsburgh, in the county of Allegheny and 5 State of Pennsylvania, have invented certain new and useful Improvements in Gas-Heaters, of which the following is a specification.

This invention relates to gas heaters and 10 more specifically to that type generally known as portable heaters or radiators, which may be carried from room to room or placed where desired and readily connected with the source of gas supply.

15 The object of the invention is to provide a heater of the type hereinafter described which is simple in construction, consisting of substantially few parts, and which may be manufactured at a low cost due to the 20 simplicity and small number of parts.

Another object is to provide a heater, the parts of which may be readily assembled or disassembled, permitting replacement or substitution when necessary.

25 Another object is to provide a heater which will permit of the radiation of a maximum amount of heat due to the special construction of the parts.

A further object is to provide a gas 30 heater or radiator with means for guarding or protecting the radiating plate from contact thus making the heater safe against burning of clothing or exposed parts of the body.

35 Referring now to the accompanying drawings forming a part of this specification, Figure 1 is a side elevation of the heater; Fig. 2 is an end view thereof;

Fig. 3 is a vertical section on the line 40 3—3 of Fig. 1;

Fig. 4 is a longitudinal section on the line 4—4 of Fig. 3;

Fig. 5 is a detail of the mixing valve on the line 5—5 of Fig. 4, and

45 Fig. 6 is a top plan view of a portion of the radiating plate.

Referring to the drawings more specifically by numerals of reference, as shown by Figs. 1 to 4, the heater comprises end 50 supporting cast metal plates 1, each of which is identical in form, having their lower portions constructed to form legs 2 and their upper portions 3 substantially circular, the latter being formed with outwardly extending circular depressions 4 spaced from the rims 5 of the portions 3.

The walls 5 of said depressed portions 4 are provided with an annular series of openings 6, thereby forming apertured extensions which permit of the entrance of 60 air from the room into the hollow radiating member hereinafter described, and escape of the heated air from within such member. Arranged adjacent the walls 5 of the depressed portions 4, but inwardly 65 disposed are integral flanges 7 generally of an inverted U-shape, these flanges serving to support the radiating or heating plate generally designated by the numeral 8. The radiating plate member consists of 70 separable sections 8¹ and 8² of cast metal, which when the heater is assembled, as shown more clearly in Fig. 3, constitute a unitary upwardly curved plate generally of an inverted U-shape the ends of which 75 rest upon the U-shaped flanges 7 upon the end supporting plates 1. This construction provides a hollow radiating member which receives all the heat from the burner, which radiating member is open at the bottom as 80 at 9, through which the flames from said burner 18 pass.

The separable sections 8¹ and 8² are provided respectively with ears 10 and 10¹ and co-operating threaded apertures, the ear 10 85 of one section overlapping the adjacent edge of the other section and being fastened by screws 11, and vice versa. By this means, the sections together constitute a unitary heating plate. For attaching the 90 heating plate to the end members 1, I provide upon alternate sections at opposite ends thereof, an ear 12 through the medium of which said sections may be connected with the end plates. It will thus be seen 95 that means are provided for detachably connecting the sections and that means are provided for detachably attaching the sections to the end plates, thus resulting in a rigid structure. The radiating plate 8 is 100 provided with apertures 14 suitably arranged to permit the passage of heat trapped thereunder.

For the purpose of protecting the radiating plate 8 against contact with any object 105 which might result disastrously by fires or burns, I provide a guard of sheet metal 15. This guard which completely covers the radiating plate and burner 18, and which conforms substantially to the outlines of 110 the end plates 1, is supported upon the latter by inwardly directed lugs 16 and an

inwardly extending flange 17. The lower portions of the sides of the guard are inwardly directed or flanged as at 24 and rest on lugs 25, thus providing an air ingress opening between such flanges 24 for the air to pass from the room around the burner 18 and into the radiating member through its open bottom 9. The upper or curved portions of the guard are provided 10 with perforations to permit of the escape of the radiated heat generated in the heating space formed by the walls of the radiating plate and the guard respectively.

The burner 18 is longitudinally disposed 15 within the lower portion of the casing formed by the sheet metal guard 15, and below, but adjacent the opening 9 of the curved radiating plate 8. The burner is supported at either end within apertures in 20 the end plates 1, being attached against accidental displacement at its rear end to an end plate by lug 19 and screw 20. A mixing valve 21 shown in Figs. 4 and 5 serves the usual function of proportioning the gas 25 and air as required. A gas tube 22 leading to a source of gas supply may be connected with the nipple 23. An opening 14' is also provided in the walls of the end plates 1 for the insertion of a taper or match to 30 light the burner 18.

The operation of my heater or radiator will now be understood. The burner 18 having been lighted, the radiating plate 8 is heated to the desired degree, and the heat 35 generated thereby passes through the openings therein and mixes with the air already heated by radiation from the plate 8. The heated air rises and passes out through the perforations in the guard. This causes a 40 current of air to be set up within the heater, cool air entering at the bottom through the space between the inwardly directed flanges 24 and through the air ingress openings in the apertured extensions, passing upwardly 45 thence into the heating space formed between the plate 8 and guard 15, and becoming more highly heated as it passes upwardly until it reaches its maximum degree of heat at the top of the heater, at which 50 time it escapes through the perforated guard and apertured extensions. Although as stated, air heated to the maximum degree will escape at the top as will be evident, and air heated to varying but increasing temperatures will escape through the guard as 55 soon as the lower apertures are reached by the air in its upward passage through the heating space.

Having thus described my invention, what 60 is claimed as new and desired to be protected by Letters Patent is:

1. A heater of the class described, comprising end members, a hollow perforated

radiator member supported by the end members, a combined perforated guard and casing member supported on said end members around and in spaced relation to said radiating member, a burner arranged in said casing member below said radiating member, and apertured extensions extending outwardly from said end members and connecting said radiating member. 65 70

2. A gas heater or radiator, comprising end members having extensions provided with air passage openings, a perforated hollow radiating member supported by said end members and having an open bottom, a combined perforated guard and casing member supported by said end members around and in spaced relation to said radiating member, said guard comprising an upper portion conforming generally to the contour of the radiating member and lower side portions having inwardly directed flanges adapted to form an air opening between the same, and a burner supported by said end members intermediate the side walls of said guard member and adjacent the open bottom of said radiating member. 75 80 85

3. A gas heater, comprising end members 90 having outwardly extending portions provided with a series of air openings therein, a hollow perforated radiating member supported on said end members and having an open bottom, a combined perforated guard and casing member inclosing said radiating member and supported by said end members around and in spaced relation to said radiating member, and a burner supported by said end members and arranged adjacent the open bottom of said radiating member, said guard comprising an upper portion conforming generally to the contour of the radiating member and lower side portions having inwardly directed flanges adapted to form an air passage between the same, said apertured extensions on said end members being in line and connecting with said radiating member. 95 100 105

4. A heater of the class described, comprising end members, a hollow perforated radiating member supported by the end members, a combined perforated guard and casing member supported on the end members around and in spaced relation to said radiating member, a burner arranged in said casing member below said radiating member, and extensions extending outwardly from said end members and connecting said radiating members, said extensions 115 120 being closed at their ends and provided with apertures in the sides.

In testimony whereof I affix my signature.
LOUIS LEBAU.
